Patented Sept. 30, 1969

215,507

PEDESTRIAN TRAFFIC SIGNAL

Jack A. Press, Jr., 3590 Rockerman Road,
Miami, Fla. 33133

Filed July 1, 1968, Ser. No. 12,567

Term of patent 14 years

Int. Cl. D29—99

U.S. Cl. D72—1

FIG. 1

FIG. 2

FIG. 4

FIG. 3

FIGURE 1 is a top plan view of a pedestrian traffic signal showing my new design.

FIGURE 2 is a front elevational view, the rear or obverse side being plain.

FIGURE 3 is a bottom plan view.

FIGURE 4 is a side elevation view and the obverse side being identical.

The lettering is shown in broken lines in FIGURE 2 for illustrative purposes only.

I claim:

The ornamental design for a pedestrian traffic signal, substantially as shown and described.
